METHOD OF MAKING AXLES

Original application filed May 15, 1929, Serial No. 363,362. Divided and this application filed November 22, 1929. Serial No. 409,094.

Our invention relates to a method of making tubular front axles for automobiles and the like.

This application is a division of our co-pending application Serial No. 363,362 filed May 15, 1929, and discloses a tubular axle of the reverse Elliot type. However the method of constructing axles disclosed in this invention is not limited to the construction of axles 10 of this particular type.

Forged axles are known and have been accepted in automotive construction. Tubular axles of the Elliot type are also known.

In such known tubular axles the end yoke 15 and spring pad are forged from solid metal and the scrapping of considerable metal is entailed in the process of machining. This is avoided in our method of construction as the spring pads are of pressed steel and the metal 20 in the end of the tubing can be forged very nearly to the size required with much less work or machining and less waste of metal.

Our method of constructing axles may also be employed in axles of the Elliot type and 25 constitutes an improvement over devices of the prior art.

In such tubular axles of the prior art the tubing is of the same section from end to end whereas in the axle made in accordance with 30 the teachings of our invention the arms are upset from a region under the spring pads to the outer ends thus strengthening and stiffening the axle where the maximum bending moment occurs.

As compared with an axle of the same strength, an axle made in accordance with the 35 teachings of our invention is much lighter than an axle of either the solid forged type or the prior known tubular axles, for example, the particular embodiment herein shown is at least twelve pounds lighter than the corresponding size of forged axle. This saving in unsprung weight is, of course, a great advantage as is well known to those skilled in the 40 art.

In carrying out our invention, we upset the 45 ends of a tubular blank by endwise forging to give the desired strength to the arm under the spring pad and the part of the arm extending outwardly towards the wheels. Forged

knuckle pieces are inserted in the end of the tube and secured therein by one of a number of ways, as, for example, by welding, forging pinning, or a combination of these actions.

The axle is then formed to shape and the 55 spring pads are welded in place. The spring pads are preferably made of sheet metal stampings, although for certain purposes forgings may be used.

The forming is preferably done in a press, 60 which, upon forming the axle, quenches it and holds it to form. This provides both heat treatment and prevents warping.

Now in order to acquaint those skilled in the art with the manner of constructing an 65 axle in accordance with the teachings of our invention, we shall describe in conjunction with the accompanying drawings a specific embodiment of the invention.

In the drawings:

Figure 1 is a side view of the upset blank with the metal pieces welded in position in the ends thereof;

Figure 2 is a side view of the completed axle;

Figure 3 is a longitudinal section through the same;

Figure 4 is a transverse section through one of the arms taken on the line 4-4 of Figure 3;

Figure 5 is a fragmentary view showing the manner of attaching the springs to the spring seat;

Figure 6 is a fragmentary side view of a modified form of spring seat and shock absorber hanger;

Figure 6a is a plan view of the same;

Figure 7 is a fragmentary longitudinal section through a modified form of axle employing the forged knuckle seat;

Figure 8 is a longitudinal vertical section through the blank which is employed in manufacturing the axle;

Figure 9 is a similar section through the blank after the first step of reducing the 95 diameter of the ends;

Figure 10 is a similar section of the tube after the first upsetting operation;

Figure 11 is a similar view of the end of the tube showing a second upsetting opera- 100

tion to adapt the tube to be attached to the knuckle piece by a forging or pressing operation;

Figure 12 is a longitudinal section through the tube and the knuckle piece showing the metal of the tube pressed or forged into the recesses in the shank of the knuckle piece;

Figure 13 is a section taken on the line 13—13 of Figure 11 showing the excesses of metal produced by the second upset operation;

Figure 14 is a section taken on the line 14—14 of Figure 12 showing the projection of the tube walls inwardly to grip the shanks 15 of the knuckle piece;

Figure 15 is a longitudinal vertical section through the end of the tube showing a modified form of connection between the tube and the shank of the knuckle piece;

Figure 16 is a side view of a forming and quenching press;

Figure 17 is a front elevational view of the dies employed in the press of Figure 16; and

Figures 18 and 19 are a side view and a bottom plan view, respectively, of the pressed metal spring clip.

Referring now to Figures 2, 3, 4 and 5, the completed tubular axle is shown in these Figures and it comprises a tubular member 1 having the arms 2 and 3 with knuckle pieces 4 and 5 secured to the ends of the arm. The knuckle pieces 4 and 5 are drilled as indicated at 6 and 7 for the reception of knuckle pins for the front wheels.

The bores 6 and 7 are set at an angle so that the axis of the knuckle pin intersects the supporting surface at a point somewhat in advance of or at the bearing of the tire upon the road as is well known to those skilled in the art. The tubular member or body 1 is constructed of a piece of seamless steel tubing, the blank therefor being shown in Figure 8. The tube is initially of approximately two and one fourth inches in diameter and has a wall thickness of approximately three sixteenth inches. The outer ends or arms 2 and 3 are thickened by endwise upsetting at points lying within the spring seats 8 and 9 as may be seen in Figure 3. The outer ends of the arms 2 and 3 are reduced in diameter externally and are formed into the shape of tubular conical sockets as indicated at 12 and 13, the walls being brought to a maximum thickness at the inner ends 55 of the sockets as indicated at 14 and 15. The sockets 12 and 13 receive the shanks 16 and 17 of the knuckle pieces 4 and 5.

The sockets are reamed out and the shanks 60 16 and 17 machined and pressed into the ends of the tube (that is, forced into the sockets) and are then secured by circumferential wells as at 18 and 19 to the knuckle pieces, shoulders being provided on the 65 knuckle pieces adjacent the ends of the tube

to provide a V-shaped groove which is filled with the welding metal.

The shanks 16 and 17 are pinned to the ends of the tubes preferably by welded pins or plugs as shown in Figure 4 although tapered or riveted pins may be employed if desired.

The welding is accomplished by drilling a recess at each side through the socket and into the body of the shank and then producing by welding, as by means of an electric arc, the plugs 20 and 21 which at the same time are fused to bolt the body of the shank and the walls of the socket. Thereby, the circumferential or hoop strength of the socket is not impaired and it is not necessary to drill away the body of the shank to an extent which would materially weaken the same. The pins 20 and 21 are placed principally on the horizontal neutral axis of the axle so that the beam strength of the axle is not materially impaired. The welded pins 20 and 21 are highly advantageous in taking the torque reaction of the wheel upon the arm of the axle.

The inner welding line of the plug through the shank lies below the dividing line between shank and socket so that the weld is not in shear but the body of the plug such as 20 or 21 is in shear at said dividing line.

The strength of such riveted plugs or pins 20 and 21 in shear is very high with the result that excellent connection can thus be made. The shanks are pressed into the ends of the arms when the shaft of the axle is straight (that is, as shown in Figure 1) and the taper between the parts facilitates a very close mechanical fit.

The spring pads 8 and 9 which are shown more in detail in Figures 18 and 19 are preferably made of pressed sheet metal or plate stock and comprise a flat platform portion 23 upon which the lower leaf of the leaf spring 24 rests.

A pair of wings 25 integral with the platform portion 23 are formed into a cylindrical shape to fit the outer cylindrical surface of the axle, the ends of the platform portion 23 extending outwardly, preferably beyond the diameter of the tube so as to form corners 26 in which U-bolts 27 and 28 are adapted to lie.

The U-bolts are connected together by yokes 29 and 30, the yokes being just long enough to permit the leaf spring to lie between the sides of the shanks of the bolts and the seats or saddles 25—25, extending around the circumference of the tube less than halfway so that the said seats or saddles 25 are embraced between the shafts of the U-bolts 27 and 28. This provides a light and compact spring seat. These curved wings which form the saddles or seats 25—25 are then welded along their edges to the tubular member 1 and with such welding the seats form rigid support against which the U-bolts may draw to secure a very firm grip upon the axle. The platform portion 23 is provided with a hole 32

at the center for the reception of a pin or stud in the center of the spring.

In attaching the spring seat, the axle and clips or seats 8 and 9 are held in a jig while the edges 33 are fastened by hand welding and then the circumferential welds along the edges 35 of the saddles or seats 25 are machine-welded. Obviously, this could be done by hand. The extended welds along the edges 10 provide a secure attachment between the spring seat and axle.

In Figure 6, I have shown a modified form of spring seat in which the spring seat is formed of a forging. In this case, since the 15 bottom is a solid cylindrical surface, extended wings or seats are not required and the weld 37 at each side does not interfere with the location of the bolt as shown in Figure 6, so that the cylindrical seat can be more extensive and can extend over a wider arc on 20 the surface of the tube. A weld 37 forms a fillet in the corner between the side wall of the seat member 38 so that it need not interfere with the shank of the U-bolts such as 27 25 and 28.

As shown in Figures 6 and 6^a, such forged spring seat may be provided with an arm 40 forming a shackle 39 for attaching the strap of a shock absorber or rebound check, such 30 shackle having an eye 41 or being otherwise formed to receive the end of a strap or of a cable which may be employed for this purpose. If a two-way shock absorber is to be employed the arm 40 may bear a pin or the 35 like connection for the shock absorber.

In the process of manufacture of the axle, the blank 10 shown in Figure 8 is a piece of seamless steel tubing and while in the particular axle which I have built a diameter 40 of two and one fourth inches and a wall thickness of three sixteenth inches have been employed, it is to be understood that these dimensions are optional.

The end of the tube is first swaged down 45 as by rolling to taper the outer end as indicated at 45 in Figure 9. This results in a slight elongation of the blank and a slight thickening of the walls of the outer end which later forms the arms 2 and 3. This rolling down is preferably accomplished at each end either simultaneously or individually and is preferably done hot. The tube is then brought to a proper forging heat and is upset endwise to thicken the walls about the 50 entire periphery of the part which is upset, at a point within the place where the spring seat, such as 8 or 9, is later attached.

At the same time, or by subsequent operation, the upsetting of the outer end to form 55 the socket 12 is accomplished, the inside diameter of the socket being held to a definite shape by a mandrel and maximum wall thickness of the tubular blank being produced just back of the socket as indicated at 60 14 in Figure 10.

The sockets 12 and 13 are then reamed out to an accurate diameter and the shanks such as 16 and 17 of the knuckle pieces 4 and 5 are accurately machined and pressed in with a press fit into the sockets 12 and 13, these parts being carefully held in alignment and the shaft or body of the tube being straight as indicated in Figure 1. Then the circumferential welds 18-18 are formed, this operation preferably being performed by machine although it may be done by hand.

Then the pockets for receiving the welds 20 and 21 are drilled and the said welds are made between the shank and walls of the socket. The drilling of the pockets may occur before the circumferential welds 18 and 19 are made so that the two welding operations may be accomplished at substantially the same time.

This leaves the axle in the shape shown in Figure 1 and it is now ready for forming. The axle is then heated preferably throughout its entire length or it may be heated only at the point where it is to be bent, that is, just outside of the place where the spring seat will later be fastened. Then it is placed in the press shown in Figure 16 and laid in the die 47 which has a groove to receive the axle as shown in Figure 1. The lower die 47 has a spring follower plate 48 which is adapted to be held in position by suitable follower springs indicated at 49. This spring follower plate 48 is provided with a seat for receiving the shaft or body of the axle and to hold the same with sufficient 90 rigidity that the upper die member 50 in engaging the body of the axle secures a firm grip upon the same. Then the upper die member 50 forces the axle down to bend the 95 axle into the shape shown in Figure 2.

The lower die member 47 is preferably mounted upon a plunger member 51 which plunger member may be connected to a hydraulic piston in a cylinder 52 and subjected to a predetermined hydraulic pressure in a connected accumulator 53, subject to air-pressure of a predetermined value.

This holds the lower die member 47 in elevated position with a predetermined force which is sufficient in cooperation with the upper die member 50 to form the body of the axle to the desired shape.

A box member 54 surrounds the plunger and this box or chamber contains a bath of quenching liquid 55 which may be water or oil, or the like, the level of which is below the top of the lower die member 47 when the latter is in elevated position.

The upper die member 50 is preferably mounted on a hydraulic plunger 56 having an operating cylinder 57 capable of exerting a pressure in excess of the predetermined pressure, sustaining the lower die member. The operation is as follows:

The lower die member 47 being elevated

as shown in Figure 16 and the axle member being placed in the lower die member, hydraulic pressure is admitted to the upper end of the piston connected to the plunger 56 causing the plunger to travel downwardly to carry the upper die member 50 into engagement with the body of the axle, depressing the follower plate 48 and forcing the axle to conform to the shape of the die. Further pressure overcomes the resistance of the plunger 51 and both dies are then brought down into the bath 55 with the axle held between them in such position that it is incapable of warping during cooling and the axle is thereby quenched and at the same time held to the desired shape.

The pressure is then released upon the upper side of the piston of the plunger 56 and the pressure on the lower side of the plunger 51 causes the same to be raised to its upper limit, and then the pressure applied to the lower side of the piston connected to the plunger 56 causes the die member 50 to be raised to clear the lower die and the contained axle. The axle is then removed and thereafter the spring seats 8 and 9 are attached by welding as previously described to provide the completed axle shown in Figure 2.

In Figure 7 I have shown a modified form of the axle of the Elliot type where the forked knuckle piece 58 is provided. The arm 2 is thereby shortened but the formation of the socket 12, the peripheral weld 18 and the pin welds 20 and 21 may be formed in the same manner and the spring seat 8 attached, all as previously described. The forked knuckle piece may then be drilled and finished just as the reverse Elliot axle shown in Figure 2 may be drilled and machined to finish the axle.

In Figures 11 to 14 inclusive, we have shown the manner of attaching the knuckle piece and the end of the arm by pressing or forging operation to interlock the shank 60 of the knuckle piece 61. In this case, after the operation of forming the tapered socket 12 of Figure 10, the end of the arm is upset in a die to produce the protuberances 63-63 upon the outside walls of the socket. The inside walls are tapered as in Figure 10, the sockets being, however, shortened by such operations, to provide the increased metal for the protuberances 63.

The shank 60 is provided with parallel corrugations or grooves across the top and bottom of the shank as indicated at 64, the shank otherwise being machined and being pressed into the socket. The next operation is a pressing or forging of these protuberances 63 into the recesses 64 on the inside wall of the socket. That is to say, the outside wall of the socket is brought to a circular form tapered outside.

The excess metal which was contained in the protuberances 63 which formed ridges of

lunar shape upon the top and bottom of the sockets is thereby forged into the pockets or corrugations 64 as indicated at 65 in Figure 12. This disposal of the metal on top and bottom places it in a position where it has maximum value for increasing the moment of inertia in bending. The operation of forcing the metal inwardly may be performed in a suitable two-part die engaging top and bottom of the outside of the socket.

Instead of grooves such as 64 across the top and bottom, the shank 66 of the knuckle piece 67 shown in Figure 15 may have a series of frusto-conical or frusto-pyramidal recesses 68 formed therein and these may be disposed about the periphery of the shank, and by an upsetting operation similar to that shown in Figure 11 metal may be provided on the outside of the socket which is then forced into such recesses 68-68 to provide the interlocking projections 69-69 connecting the socket and the shank 66 firmly together. The outer margins of the sockets and the shanks may be welded if desired but if properly forged this is not necessary.

An advantage of the welded form is that the inside of the body is completely closed off from the outside so that moisture cannot get into the inside and corrode the axle.

Tests made upon this axle indicate its superiority in performance as against axles of the prior art. The tubular shape of the body of the axle is highly desirable because of the maximum strength against bending in any direction and also because of its high torsional strength.

The bent ends or arms 2-3, which are connected to the wheels form crank arms which particularly under the action of heavy breaking of the vehicles tend to twist the axle with respect to the spring. The welding of the seats 8 and 9 to the body of the axle provides a hold which is highly resistant to such torsional stresses as well as to other stresses which are incidental to the use of the axle. We do not intend to be limited to the details shown and described.

What we claim is:

1. The method of forming a tubular axle which comprises tapering the end portions of the tubular blank, upsetting said end portions to increase the wall thickness and to form a tapered socket in the outer end, forging a knuckle piece with a tapered shank, driving said shank into the socket, and forming a peripheral weld about the margins of the socket and shank.

2. In the method of forming a tubular axle out of a blank of seamless tubing which comprises tapering an end portion of the blank, upsetting said end portion to increase the wall thickness thereof and to form a tapered socket, forging a knuckle piece with a tapered shank, driving said shank into the

socket and welding the socket and shank together.

3. The method of forming a tubular axle which comprises tapering the end portion of a tubular blank, upsetting said end portion to increase the wall thickness thereof and to form a socket, forming a knuckle piece with a shank, inserting said shank into the socket, forming a recess through the wall of the 10 socket and into the shank and welding metal to the walls of said recess to unite the shank and socket.

4. The method of forming a tubular axle which comprises tapering the end portions of a tubular blank, upsetting said end portions to increase the wall thickness thereof and to form a socket in the outer end, forming a knuckle piece with a shank, introducing said shank into the socket, forming a peripheral 15 weld about the margins of the socket and the shank, forming a recess through the walls of the socket and into the shank and welding metal to the walls of said recess to fill the 20 same.

25 5. In the method of forming a tubular axle the following steps, viz., tapering the end portions of the tubular blank, upsetting said end portions to increase the wall thickness thereof and to form tapered sockets, forging 30 knuckle pieces with tapered shanks, driving said shanks into the socket, forming peripheral welds about the margins of the socket and the shank, forming recesses through the walls of the socket and into the shank and 35 welding metal to the walls of said recesses to fill the same.

6. The method of forming a tubular axle which comprises tapering the end portion of a tubular blank, upsetting said end portion to 40 increase the wall thickness thereof and to form a socket, forming a knuckle piece with a shank, forcing said shank into said socket, forming a recess through the wall of the 45 socket and into the shank and welding metal to the walls of said recess to fill the shank.

7. The method of forming a tubular axle out of a blank of thin walled tubing which comprises upsetting the walls of the blank to thicken them at the points of maximum stress, 50 tapering the end portions of the blank, upsetting said end portions to increase the wall thickness thereof and to form a tapered socket, forging a knuckle piece with a tapered shank, driving said shank into the socket, and welding 55 the socket and shank together.

8. The method of forming a tubular axle out of a blank of seamless tubing which comprises heating the blank at the points at which the spring supports are to be located, 60 endwise upsetting the walls of the blank at those points to thicken them about the entire periphery of the blank, heating the end portions of the blank, and tapering and upsetting said end portions to form them to the desired shape and wall thickness.

9. The method of forming a tubular front axle from a thin walled seamless tube which comprises heating, and endwise upsetting the tube to thicken its walls about the entire periphery of the tube and form a spring support, heating, tapering, and upsetting the end sections of the blank, and forming the end sections to shape. 70

10. The method of forming a tubular front axle from a thin walled tubular blank which comprises, heating and endwise upsetting the blank to thicken its walls substantially uniformly circumferentially and form a spring support, heating, tapering, and upsetting the end sections of the blank, forming the end 80 sections to shape, forging a knuckle piece, and welding that knuckle piece into the end section of the blank. 75

11. The method of forming a tubular axle from a blank of thin walled tubing which comprises upsetting the walls of the blank to thicken them by moving metal inward to decrease only the perimeter of the inside of the tube, tapering the end portions of the blank, upsetting said end portions to increase the 90 wall thickness thereof and to form a tapered socket, forging a knuckle piece with a tapered shank, driving said shank into the socket, and welding the shank and socket together. 85

12. The method of forming a tubular front axle from a thin walled tubular blank which comprises, heating a section of the blank, supporting the blank at that heated section, upsetting the blank to thicken the walls at that section by decreasing the perimeter of only 95 the inside surface, heating the end section of the blank, and upsetting the end section and forming said end section to shape. 100

13. In a method of making a tubular axle, the combination of the following steps, heating a thin walled tubular blank, upsetting the wall by endwise pressure to produce a thickened wall back of one end thereof at a point where a spring seat is to be located, forming a spring seat with a concave bottom wall fitting the wall of the blank where it is upset, and welding the edges of the seat to the thickened wall of the blank. 110

In witness whereof, we hereunto subscribe our names this 19th day of November, 1929.

EDMUND C. MOGFORD.
